CLAIM

The ornamental design for a spa valve handle with knob, as shown and described.

DESCRIPTION

FIG. 1 is a top side perspective view of a first embodiment of a spa valve handle with knob showing our new design on a first pipe fitting.

FIG. 2 is a front view of the design shown in FIG. 1.

FIG. 3 is a rear view of the design shown in FIG. 1.

FIG. 4 is a left side view of the design shown in FIG. 1.

FIG. 5 is a right side view of the design shown in FIG. 1.

FIG. 6 is a top view of the design shown in FIG. 1.

FIG. 7 is a bottom view of the design shown in FIG. 1.

FIG. 8 is a top side perspective view of a second embodiment of a spa valve handle with knob showing our new design on a second pipe fitting.

FIG. 9 is a front view of the design shown in FIG. 8.

FIG. 10 is a rear view of the design shown in FIG. 8.

FIG. 11 is a left side view of the design shown in FIG. 8.

FIG. 12 is a right side view of the design shown in FIG. 8.

FIG. 13 is a top view of the design shown in FIG. 8; and,

FIG. 14 is a bottom view of the design shown in FIG. 8.

The broken lines shown in the figures are for the purpose of illustrating portions of the spa valve handle with knob and form no part of the claimed design.
